UNITED STATES PATENT OFFICE.

ALEXANDRE FRIEDMANN AND EMILE D'ERLANGER, OF PARIS, FRANCE.

IMPROVEMENT IN BOILER-FURNACES.

Specification forming part of Letters Patent No. 39,640, dated August 25, 1863.

To all whom it may concern:

Be it known that we, ALEXANDRE FRIEDMANN and FRÉDÉRIC EMILE D'ERLANGER, both of Paris, in the Empire of France, have invented a new and useful Improvement in Steam-Boiler Furnaces; and we do hereby declare that the following is a full, clear, and exact description of the construction and operation of the same, reference being had to the figures of the annexed drawings, making a part of this specification—that is to say:

Our invention consists in the application, as hereinafter described, to the fire-boxes of steam-boiler furnaces, of an inner mantel or diaphragm, so arranged as to form a reverberating chamber, in which are effected the heating of the atmospheric air required for the combustion of the smoke and its distribution over the ignited surface of the fuel on the grate.

Figures 1, 2, 3, 4 of the annexed drawings represent, as example, an application of the invention to an ordinary locomotive-furnace. Fig. 1 is a longitudinal section of the fire-box, with its mantel. Fig. 2 is a horizontal section of the same through the line A B. Fig. 3 is a cross-section through C D. Fig. 4 is an end view.

H is the mantel, constructed of thick sheets of wrought or cast iron, copper, or steel, descending from over the furnace-door to a certain distance above the fire-bars, varying from ten to twenty inches, according to the average depth of the fuel layer. In no case should the thickness of the metallic sheets be less than one-quarter of an inch, experience having proved this to be the lowest point at which they can retain a sufficiency of caloric for heating the amount of air required.

a c are brackets and bolts, by which this mantel is so attached to the furnace as to be readily dismounted and replaced at will. The surfaces of the mantel, in close proximity to the grate, are provided to a height of at least four inches with strong sheet-metal linings, as in D, or, again, with a cast-iron band, to enable them to resist the direct action of the fire. The thickness of metal at this point should never be less than three-fourths of an inch.

P' P' are two ports, fitted to the fire-box to permit of inspecting at will the combustion in the sides of the furnace, as also the tube-plate

Q Q, which is concealed by the mantel from the fire door P. If preferred, these ports may be replaced by a door set in the back of the mantel itself. A small self-closing trapway may also, if desired, be formed in each side of the mantel, to facilitate the uniform charging of the fuel in the sides of the grate. During the stoppages the combustion is kept up by aid of a blower, with which the boiler is provided.

The fuel is supplied to the furnace by the fire-door P, which is always kept more or less open to allow the passage of the air. The air thus admitted into the mantel, absorbing the caloric of the metal, is heated to a high degree, and, passing downward toward the fuel layer, mingles with the gaseous products of the combustion, which are entirely consumed. The introduction of air is regulated at will by the notched bar K, which maintains the door P in the required position. When the action of the chimney is suppressed by the stoppage of the engine, the blower may be opened to produce a draft, which forces the air passing by the fire-door to turn over in the entire length of the mantel.

Figs. 1bis, 2bis represent, in longitudinal section and plan, a semi-conical mantel constructed on the same principle as that above described.

Figs. 5, 6, 7 represent, on a reduced scale, an application of the invention to furnaces in which the door is in such close proximity to the grate and to the roof of the fire-box as to leave insufficient space for the secure attachment of the mantel to the inner face of the latter. In this arrangement the mantel is modified in form, as shown in the drawings, and is firmly bolted to the roof and front of the fire-box, thus assuring the necessary degree of rigidity, which, from the construction of the furnace, it would be difficult to obtain by the single front attachment shown in the preceding figures.

The door P may be constructed on the same principle as those above described; or, when sufficient space exists between it and the roof of the fire-box, it may be reserved solely for the introduction of the fuel, a small port, as in W, Fig. 8, or a series of apertures, being formed above for the admission of air.

Fig. 8 represents an application of the invention to furnaces, in which, as in certain

descriptions of portable and stationary engines, the door is set close to the grate and at a considerable distance from the roof of the fire-box. In this application the door P remains closed, as in ordinary furnaces; but above it is formed a small port, W, of similar construction to that seen in P, Figs. 1, 2, 4, and reserved solely for the admission of air into the mantel into which it issues. When so desired, and permitted by the construction of the fire-box, this second door may be replaced by simple air-apertures, as already described.

It will be understood from the preceding description that the main object of our invention is to obtain the intimate mixture of highly-heated air with the products of combustion at the moment of their disengagement, and that to effect this the proportions, position, and resisting-power of the mantel are points of the greatest importance. Thus, it must contain a large quantity of matter to enable it to contain a large quantity of caloric; it must present a large heating-surface to enable it properly to divide the air to be heated; it must be a good conductor to enable it to give up its caloric with facility, and it must be rigid enough to support, without losing its shape, a high degree of temperature.

Several essential precautions must be observed in the construction and arrangement of the mantel to enable it to resist the destructive action of the fire, thus: First, its surfaces must be kept free from pressure; secondly, it must be firmly secured in position, while so fixed as to be readily mounted and dismounted at will, due allowance being made for the independent dilatation and contraction of the fire-box to which it is applied; thirdly, it must be constructed of material of high density, conductibility, and heat-resisting power, the minimum thickness of such material in its thinnest parts being one-fourth of an inch, and in those parts in proximity to the grate three-fourths of an inch, the latter thickness being extended to a minimum height of four inches; fourthly, the surfaces which do not come in direct contact with the fire-box should be inclined toward

the surface of the fuel, and their resistance to vertical flexion must be sufficient to enable them to withstand the highest degree of temperature to which they can possibly be exposed.

It should be well understood, in conclusion, that the above-noted thicknesses of mantel metal (one fourth inch and three-fourths inch) are stated as the lowest consistent with any degree of efficiency, and that they should always be increased in practice, according to the temperature to which the apparatus is to be exposed. Thus, for instance, in the application to locomotive-furnaces, in which the metal is most liable to deterioration, the thickness of the upper part of the mantel may be carried to one-half or three-quarters of an inch, and in the lined portion, near the grate, to one and a-half, one and three-quarters, or even two inches.

In applications to portable and other engine furnaces, in which the apparatus is less exposed to wear, the thicknesses may vary, according to circumstances, between the limits above laid down.

We are aware that attempts have hitherto been made to consume smoke in boiler-furnaces by aid of vaultings and other capacities offering some general resemblance to the mantel above described; but in no case have any such arrangements satisfied the several essential conditions herein laid down.

We therefore claim and desire to protect by Letters Patent—

The application, substantially as herein set forth, and shown in the drawings, to the fire-boxes of steam-boiler furnaces, of an inner mantel in metal, so arranged as to form an inclined diaphragm or reverberating chamber, in and by which are effected the heating of the air required for the combustion of the smoke and the distribution of this air over the ignited surface of the fuel on the grate.

ALEX. FRIEDMANN.
EMILE D'ERLANGER.
